Primary Examiner — W. A. Teddy Falloway*Assistant Examiner* — Melissa A Santos(74) *Attorney, Agent, or Firm* — Sand, Sebolt & Wernow Co., LPA(57) **CLAIM**

The ornamental design for a vessel, as shown and described.

DESCRIPTION

FIG. 1 is a front perspective view of a vessel in accordance with our design;

FIG. 2 is a front elevation view thereof;

FIG. 3 is a rear elevation view thereof;

FIG. 4 is a first side elevation view thereof;

FIG. 5 is a second side elevation view thereof;

FIG. 6 is a top plan view thereof;

FIG. 7 is a bottom plan view thereof;

FIG. 8 is a front perspective view of the vessel showing the vessel receiving an exemplary candle therein; and,

FIG. 9 is a front perspective view of the vessel showing an exemplary lid closing a top end of the vessel.

The broken lines illustrate environmental structure which form no part of the claimed design.

1 Claim, 6 Drawing Sheets(56)
